UNITED STATES PATENT OFFICE.

EMIL ELMIGER, OF DETROIT, MICHIGAN, ASSIGNOR TO THE FARRAND & VOTEY ORGAN COMPANY, OF SAME PLACE.

DESIGN FOR AN ORGAN-CASE.

SPECIFICATION forming part of Design No. 32,512, dated April 10, 1900.

Application filed March 12, 1900. Serial No. 8,403. Term of patent 7 years.

To all whom it may concern:

Be it known that I, EMIL ELMIGER, a citizen of the United States, residing at Detroit, in the county of Wayne and State of Michigan, have invented a certain new and original Design for Organ-Cases, of which the following is a specification, reference being had therein to the accompanying drawings, in which—

Figure 1 is a perspective view, and Fig. 2 is a cross-section.

The body of the case is substantially rectangular in plan and comprises a lower portion A and a forwardly-overhanging upper portion B. In the rear is a continuous vertical wall C, common to both portions A and B, and at its upper end this wall joins with a flat top D. The end walls E are provided with forwardly-projecting base portions *a*, at the outer end of which are arranged vertical columns F,

extending upwardly to the overhanging portion B. At the top of the end walls are wings or projections G, extending upward above the top at the rear of the case and curving downward toward the front.

The leading feature of the design is the body having the wings at opposite ends extending above the top in the rear of the case and inclining downward toward the front.

What I claim as my invention is—

The design for an organ-case substantially as herein shown and described.

In testimony whereof I affix my signature in presence of two witnesses.

EMIL ELMIGER.
